US00D628660S

(12) **United States Design Patent**
Verheem

(10) **Patent No.:** **US D628,660 S**
(45) **Date of Patent:** **** Dec. 7, 2010**

(54) **EXERCISE DEVICE**

(75) Inventor: **Johann B. Verheem**, Carlsbad, CA (US)

(73) Assignee: **Fitness IQ LLC**, Vista, CA (US)

(**) Term: **14 Years**

(21) Appl. No.: **29/341,461**

(22) Filed: **Aug. 5, 2009**

Related U.S. Application Data

(63) Continuation of application No. 12/508,921, filed on Jul. 24, 2009.

(51) **LOC (9) Cl.** **21-02**

(52) **U.S. Cl.** **D21/681**

(58) **Field of Classification Search** **D21/662, D21/680–684, 692, 694; 482/44–46, 57, 482/98, 105–108, 110–111, 114–115, 148**

See application file for complete search history.

(57) **CLAIM**

The ornamental design for an exercise device, as shown and described.

DESCRIPTION

FIG. 1 is a perspective view of an exercise device showing my new design;

FIG. 2 is a front elevation view thereof; and,

FIG. 3 is a side elevation view thereof.

The broken lines illustrate environmental elements of an exercise device that form no part of the claimed design.
